UNITED STATES PATENT OFFICE

WILLIAM K. RANKIN, OF LANSDOWNE, PENNSYLVANIA, ASSIGNOR TO GENERAL ELECTRIC COMPANY, A CORPORATION OF NEW YORK

HYDRAULIC OPERATING MECHANISM

Application filed September 11, 1929. Serial No. 391,963.

My invention relates to hydraulic operating mechanism, and more particularly to operating mechanism for effecting operation of circuit breaker mechanism.

5 A principal object of my invention is the provision of hydraulic operating mechanism for effecting substantially uniform and positive movement of a member, as a switch operating member of the oil or fluid-break type, 10 wherein it is desirable that the switch contacts be actuated to closed position by a substantially constant force.

15 A further object is the provision of pressure relief means whereby the force tending to move the switch member to closed position is immediately diminished to an inappreciable value upon the occurrence or existence of an abnormal circuit condition.

20 A further object is the provision of releasing mechanism for concurrently tripping the switch operating member and decreasing the fluid resistance to its opening movement.

25 A further object is the provision of switch operating mechanism which shall operate efficiently and smoothly, and which shall be immediately responsive to abnormal circuit conditions to permit opening movement of the switch.

30 My invention will be more fully set forth in the following description referring to the accompanying drawings, and the features of novelty which characterize my invention will be pointed out with particularity in the claims annexed to and forming a part of this specification.

35 Referring to the drawings, Fig. 1 is an elevational view, partly in section, of hydraulic operating mechanism; and Fig. 2 is a cross-sectional view taken along the line 2-2 of Fig. 1.

40 Referring to Fig. 1, a main operating member 1 is adapted to be operatively connected to mechanism (not shown), as switch mechanism, for example, the mechanism being operated by reciprocatory movement of the member 1. Reciprocation of member 1 is effected by a fluid motor comprising a piston 2 disposed within a piston cylinder or 45 chamber 3, the piston being normally biased

towards the position shown by a spring or equivalent resilient means 4.

Fluid introduced under pressure through the fluid passage 5 into the lower or working end of cylinder 3 is effective to move the piston 2 upwardly against the tension of spring 4. To this end there is provided a motor 6, adapted to be energized in a manner hereinafter described from a source of current 7, mounted upon an impeller housing 8 which in turn is mounted upon and forms a top section of a fluid reservoir 9, containing a non-compressible fluid 9a, as oil. The motor 6 when energized is adapted to rotate the shaft 10 which is vertically mounted with respect to the oil reservoir and impeller housing. A fluid impeller or pump 11, as of the centrifugal type, is disposed within the impeller housing and is mounted upon the shaft 10 so as to be rotated thereby. A fluid-feed device 12 comprising a helical worm or screw, or equivalent structure, is likewise mounted upon shaft 10 in such a manner that energization of motor 6 tends to lift the liquid 9a from the reservoir into the impeller housing. The pitch of the helical worm, however, is such that the fluid may be forced upwardly through the casing 13 into the impeller housing only when the speed of the motor 6 has been brought up to its normal or predetermined speed. As illustrated, casing 13 comprises a conduit extending appreciably beneath the normal level of the liquid in the reservoir and is open at its lower end, its upper end communicating with the impeller 11. When the motor 6 is operated at comparatively low speeds, as when it is being brought up to speed, the liquid is not forced upwardly into the impeller housing, but runs out of the screw after a certain hydraulic head has been built up within casing 13.

45 As the speed of motor 6 increases, the hydraulic head within casing 13 becomes higher until there is a continual fluid feed from reservoir 9 to an impeller chamber 14 from whence it is forced by the impeller 11 through openings 14a (Fig. 2), into an outer passage 14b of the impeller housing communicating with passage 5 leading to the 50

working end of cylinder 3. Accordingly, rotation of motor 6 at a predetermined speed is effective to pump a substantially non-compressible liquid from the reservoir 9 to the impeller 11 which in turn forces it under pressure into the working end of cylinder 3 to actuate piston 2 and the coacting operating member 1.

Since it is generally desirable in switch mechanism that the member 1 be restrained in one of its limiting positions, and shall be released from such position in response to certain conditions, there is provided means comprising a latch 15 normally biased by a spring 16 to engage a notch 17 in the member 1, when said member has been forced upwardly a predetermined distance to effect the circuit-closing operation, for example. The latch 15 is provided with a tail-like extension 17' adapted to cause collapse of a switch-locking toggle 18 when the latch 15 moves into notch 17. A movable switch member 19 connected to toggle 18 and pivoted at 20, is adapted to be biased by a tension spring 21 in a clockwise direction to break contact with a stationary contact 22 upon collapse of the toggle 18. As illustrated, the switch member 19 controls the energization of motor 6 from the source 7, the motor being deenergized by switch 19 when the member 1 has been actuated to its limiting position.

In the operation of switch mechanisms, as oil circuit breakers, for handling large power currents, it is often undesirable to attempt closure of the switch if some abnormal condition, as a short circuit, continues to persist in the circuit to be closed. It is therefore necessary to provide means which will permit the switch operating mechanism to be deenergized and to move towards open position before the switch mechanism has been actually closed, if such abnormal conditions still persist. For this purpose, there is provided means for immediately by-passing the source of pressure acting on the piston 2, thereby permitting the spring 4 to return the member 1 to the position illustrated in Fig. 1. The means above described comprises a pressure relief valve 23 having guide flanges 24 adapted for reciprocatory movement within the combined cylindrical guide and valve seat 25 disposed in the working end of the cylinder 3. Valve 23 when open permits communication between the working end of cylinder 3 and a fluid compartment 26 in communication with, and forming a part of, the main reservoir 9 through an opening 27 in the lower part of partition 28. Therefore, when valve 23 is open the fluid impelled through passage 5 is by-passed into the reservoir with the result that there is no appreciable fluid pressure acting on piston 2, notwithstanding the normal energization of the motor 6. The valve 23 is operatively connected to a lock-

ing and releasing toggle 29 adapted to be overtravelled, as illustrated, against a lug or stop member 30 secured to the reservoir casing. Toggle 29 is in turn operatively connected through a link 31 to a pivoted member 32 adapted to be actuated by a crank and a reciprocatory rod 33 connected to a magnetizable core 34 of an electromagnet 35. The core 34 is provided with a member 36 against which a spring 37 bears to normally bias the magnetizable core to the position illustrated wherein the toggle is set in its overtravelled or locking position to maintain valve 23 in firm fluid-tight engagement with its seat. Accordingly, when valve 23 is closed the fluid pressure developed by impeller 12 is effective to operate the piston.

The electromagnet 35 is adapted to be connected by a switch 38 to either the source 7 or to the secondary of the usual current transformer 39. With switch 38 in the position illustrated, the electromagnet 35 is adapted to be controlled in the usual manner in response to an overload or short circuit. For manual control of the operating mechanism, switch 38 is thrown to connect the electromagnet across the source 7. A tripping electromagnet 40, whose magnetizable core is operatively connected, as at 41, to the extension of latch 15, is connected in parallel with the electromagnet 35 so as to be actuated concurrently therewith.

The operation is as follows:

With the elements in the position illustrated in Fig. 1 wherein the switch member 19 has been moved to engage contact 22 by manual or other suitable operating means, the circuit of the motor 6 is completed to start rotation thereof. As the motor 6 is coming up to speed there will be no liquid supplied to the impeller 11 by the screw 12, thereby preventing the piston 2 from being actuated by a weak or inadequate force. In other words, the hydraulic head within casing 13 developed by the screw 12 when the motor is under speed is below the impeller casing, thereby preventing the impeller 11 from acting on other than air during its starting period. As motor 6 reaches its normal or predetermined speed a steady flow of liquid is drawn into the impeller chamber whereupon the impeller 11 forces the liquid at full normal pressure through passage 5 into the working end of cylinder 3. Due to the fact that the motor 6 is adapted to operate at substantially constant speed, the fluid pressure acting on piston 2 tending to raise the same, will be substantially constant from the beginning to the end and its stroke thereby preventing erratic or uncertain operation of the main switch contacts. As the piston moves upwardly into circuit-closing position under the continued influence of the fluid pressure developed by the impeller 11, the notch 17 in the operating member finally

moves into registry with the restraining portion of latch 15 which is biased by the spring 16 into engagement with member 1 to prevent reverse movement of the same. The latch 5 15 engages at its opposite end the toggle 18 at its mid point to cause it to collapse and permit the spring 21 to open the switch member 19. The motor 6 is thereupon automatically deenergized when the operating stroke 10 has been completed.

Let it now be assumed that an overload or short circuit occurs on the line which is to be controlled by the main switch mechanism. The current transformer 39 accordingly concurrently actuates both of the electromagnets 35 and 40. Actuation of electromagnet 35 serves to move the magnetizable core 35 against the tension of spring 37 to rotate the pivot member 31 through the rod 33 in a clockwise direction, thereby causing collapse of toggle 29 and opening of valve 23 so that the liquid in cylinder 3 may readily flow back into the lower reservoir. Actuation of the electromagnet 40 serves to rotate the latch 25 15 in a clockwise direction to release the operating member 1 and permit the spring 4 to return piston 2 to its lowermost position. Due to the fact that valve 23 is now open the remaining fluid in cylinder 3 does not offer appreciable resistance to the return movement of piston 2. The operating mechanism is adapted for another circuit-closing movement only when the overload or other abnormal condition has cleared, thereby permitting closure of valve 23 by the spring 37.

If the mechanism is operated in the normal manner to effect a circuit-closing operation but during this operation a short circuit, for example, should occur, the electromagnet 35 would be immediately actuated to open the valve 22 and thereby by-pass the source of fluid pressure back to the main reservoir. The fluid pressure acting on the piston 2 would be correspondingly diminished 45 to an inappreciable value so that the spring 4 would be effective to immediately return the piston to the open circuit position. In the event that the switch mechanism is closed and it is desired to trip it, switch 38 is thrown 50 to connect the electromagnets across source 7, thereupon concurrently energizing and actuating them to open the mechanism in the same manner as in the case of a short circuit or overload. Upon manual operation 55 of the mechanism, switch 38 is subsequently returned to its original position connecting the electromagnets with the current transformer 39 so that the closing operation may be initiated by movement of the switch member 19 to complete the motor circuit. The movement of switch member 19 to circuit-closing position likewise moves the toggle 18 to its overtravelled or locking position 60 from which it may be moved by the actuation of latch 15.

It shall be understood that various modifications and changes may be made in the operating mechanism as illustrated without departing from the spirit of my invention; for example, the electromagnets 35 and 40 70 may be rendered responsive to abnormal conditions other than overload or short circuit, such as low voltage, current reversal, etc.

What I claim as new and desire to secure 75 by Letters Patent of the United States is:

1. Hydraulic switch operating mechanism, comprising a source of fluid pressure, a switch operating member adapted to be moved to circuit-closing position by said fluid pressure, means for directing fluid pressure to said switch member when a predetermined normal pressure obtains thereby effecting operation of said member at a constant pressure, and pressure relief means for decreasing said pressure in response to an abnormal circuit condition, said member thereupon being permitted to move towards its open circuit position. 80 85

2. Hydraulic operating mechanism comprising a fluid impeller, a main operating member adapted to be actuated by fluid pressure developed by said impeller, means for engaging and restraining said member in its operated position, and pressure relief means associated with the main operating member, said restraining means and pressure relief means adapted to be concurrently actuated to permit reverse movement of the operating member in response to a predetermined condition of the apparatus controlled by said member. 90 95 100

3. Hydraulic operating mechanism comprising a fluid impeller, a fluid reservoir associated therewith, a fluid-feed device operatively connected to the impeller for delivering fluid from the reservoir to the impeller upon attainment of a predetermined speed thereof, a main operating member adapted to be actuated at substantially constant pressure by the fluid discharged from said impeller, and means for by-passing the fluid acting on said operating member in response to a predetermined condition of the apparatus controlled thereby whereby said member is deenergized and permitted to return to its initial position. 105 110 115

4. Hydraulic operating mechanism comprising a motor-driven fluid impeller, a fluid reservoir, a fluid-feed device operable at a predetermined speed to deliver fluid from said reservoir to said impeller, a pressure actuated operating member associated with said impeller, means for engaging and restraining said member in its operated position, and means cooperating with the aforesaid means for thereupon deenergizing said motor and impeller. 120 125

5. In a switch operating system, hydraulic operating mechanism comprising a fluid im-

5 peller, a switch operating member adapted to be actuated by fluid pressure developed by said impeller, means for engaging and restraining said member in its closed position, and means cooperating with the aforesaid 5 means for thereupon deenergizing said fluid impeller.

6. In a switch operating system, hydraulic 10 operating mechanism comprising a fluid impeller, a fluid reservoir, a fluid-feed device operatively connected to said impeller for delivering fluid from the reservoir to the impeller when it has attained a predetermined speed, a switch operating member actuated 15 at substantially constant pressure by fluid discharged from the impeller, pressure relief means associated with said member, and means responsive to an abnormal circuit condition for actuating said relief means for permitting movement of the switch operating member towards open position.

7. In a switching system, hydraulic operating mechanism for effecting movement of a switch operating member to closed position comprising a fluid impeller, a piston associated with said operating member, means providing fluid communication between said impeller and the working side of said piston, and a pressure relief valve for by-passing the fluid acting on said piston in response to an abnormal circuit condition.

8. In a switching system, hydraulic operating means for effecting closing movement of a switch member comprising a fluid impeller, a piston connected to said member, means providing fluid communication between said impeller and the working side of the piston, means for engaging and restraining said switch member in its closed position, resilient means urging the member towards open position, and a pressure relief valve associated with the working side of the piston for diminishing the fluid pressure acting on the piston, said restraining means and relief valve adapted to be actuated in response to an abnormal circuit condition, whereby the aforesaid resilient means is effective to return the switch member to its open position.

9. In a switching system, hydraulic operating means for effecting closing movement of a switch member comprising a fluid impeller, a fluid reservoir, a helical worm operatively connected to the impeller for delivering fluid from the reservoir to the impeller when it has attained normal speed, means providing fluid communication between said impeller and switch member whereby said member may be actuated by constant fluid pressure, and means co-acting with said member for deenergizing said impeller when the member has been moved into circuit-closing position.

10. Circuit-closing mechanism comprising a switch operating member, a piston and

cylinder associated therewith, a fluid impeller in fluid communication with the working end of the cylinder whereby pressure developed by said impeller is effective to actuate said piston and switch operating member, a pressure relief valve disposed in the working end of said cylinder, said valve normally biased towards closed position, and electro-responsive means associated with said valve for opening the same and deenergizing 75 said piston in response to an abnormal circuit condition.

11. Circuit-closing mechanism comprising a switch operating member, a piston and cylinder associated therewith, a fluid impeller in fluid communication with the working end of the cylinder, a fluid reservoir, a fluid-feed device for delivering fluid from said reservoir to the impeller when said impeller has attained normal speed thereby effecting operation of said piston and switch operating member at substantially constant pressure, a pressure relief valve disposed at the working end of said cylinder and opening into said reservoir, latching means for engaging 80 and restraining the switch member in its circuit-closing position, resilient means for urging the switch member towards its open circuit position, and electromagnetic means operatively connected to said latching means 85 and relief valve for concurrently actuating the same to permit movement of the switch operating member to its open circuit position in response to overload or short circuit.

12. Circuit-closing mechanism comprising 100 a switch operating member, a fluid motor for actuating the same, a source of fluid pressure adapted to be operatively associated with said motor, latching means for engaging and restraining the switch operating member in its 105 circuit-closing position, a spring normally urging said member towards its open-circuit position, an electromagnet for releasing said latching means in response to energization of the same, and a pressure relief valve associated with the fluid motor for deenergizing the same when open, said valve adapted to be opened concurrently with actuation of said latching means whereby the switch operating member is biased by said spring towards its 110 open position.

13. Circuit-closing mechanism comprising 115 a switch operating member, a fluid motor for actuating the same, a source of fluid pressure adapted to be operatively associated with 120 said motor, a pressure relief valve disposed at the working end of the motor adapted when open to deenergize the same, toggle structure for maintaining said valve in its closed position, resilient means cooperating 125 with said toggle structure for normally biasing said valve toward the closed position, an electromagnet for effecting collapse of said toggle and movement of the valve to its open position in response to an abnormal circuit 130

condition, and means normally urging the switch operating member towards open position upon deenergization of said motor.

14. Circuit-closing mechanism comprising
5 a switch operating member, a piston and cylinder associated therewith, a motor-driven pump for supplying a liquid under pressure to said cylinder for actuating the piston and switch operating member, a reservoir from
10 which liquid is delivered by a fluid-feed device to the pump, said fluid-feed device operatively connected to said pump and adapted to deliver liquid thereto when the pump
15 has attained its normal speed whereby said member may be moved to its circuit-closing position at substantially constant pressure, latching means for restraining said member in said position, a pressure relief valve disposed at the working end of the cylinder, a
20 spring tending to move the switch operating member to the open-circuit position upon the opening of the relief valve, electromagnetic means for effecting movement of the relief valve to its open position, and electromagnetic
25 means actuated concurrently with said first-named electromagnetic means for releasing said latching means for permitting movement of the switch operating member to its open circuit position.
- 30 15. The combination with a switch operating member, of hydraulic mechanism for actuating said member comprising a piston and coacting cylinder, a fluid pump in operative connection with the working end of said cylinder, means for permitting the pump to attain normal speed before fluid is delivered thereto whereby fluid may be delivered to said cylinder at substantially constant pressure, means for restraining the switch operating member in its circuit-closing position,
35 pressure relief means disposed in the working end of said cylinder, and means responsive to an abnormal circuit condition for actuating both the restraining and pressure relief means, thereby permitting movement of the switch operating member to the open circuit position.
